CLAIM

The ornamental design for a rug, as shown and described.

DESCRIPTION

FIG. 1 is a front elevational view of the rug of the present invention;
FIG. 2 is a top rear elevational view of the rug of FIG. 1;
FIG. 3 is a left side elevational view of the rug of FIG. 1, the
right side elevational view being a mirror image thereof;
FIG. 4 is a top plan view of the rug of FIG. 1; and,
FIG. 5 is a bottom plan view of the rug of FIG. 1.
